UNITED STATES PATENT OFFICE.

RICHARD A. F. BEILFUSS, OF LANSING, MICHIGAN.

SPEED-REGULATOR FOR EXPLOSIVE-ENGINES.

SPECIFICATION forming part of Letters Patent No. 700,401, dated May 20, 1902.

Application filed July 15, 1901. Serial No. 68,390. (No model.)

To all whom it may concern:

Be it known that I, RICHARD A. F. BEILFUSS, a citizen of the United States, residing at Lansing, in the county of Ingham and 5 State of Michigan, have invented new and useful Improvements in Speed-Regulators for Engines, of which the following is a specification.

This invention relates to speed-regulators for engines, and while especially designed for 10 use in connection with gas or vapor engines and described in connection with such type of engine it will be apparent as the description proceeds that the speed-regulating device hereinafter described may be associated 15 with the exhaust-valve of any type of engine.

The speed-regulator contemplated in this invention is designed to operate automatically when the speed of the engine becomes 20 excessive, so that without any attention on the part of the operator or attendant the speed of the engine will be reduced and governed, thus rendering the engine safe and preventing the accumulation of successive charges of gas or 25 vapor and the explosion of the same within the engine-cylinder.

With the above general objects in view the invention consists in a speed-regulating device for engines embodying certain novel features and details of construction and arrangement of parts, as hereinafter fully described, 30 illustrated, and claimed.

In the accompanying drawings, Figure 1 is an elevation of an engine, showing the exhaust and suction valve casings in section to better illustrate the working of the speed-regulating device. Fig. 2 is a vertical sectional view of the same, taken in line with the stems of the exhaust and suction valves. 35

40 Like numerals of reference designate like parts in both views.

The speed-regulator contemplated in this invention is for the sake of illustration shown applied to a gas or vapor engine the construction of which is identical with that disclosed in a companion application for patent, 45 and it will not be necessary, therefore, to describe the engine herein further than to give a general idea of the same.

50 The engine is mounted and supported upon a suitable base 1 and comprises a cylinder-frame 2, carrying the engine-cylinder 3, in

which is mounted a reciprocating piston-head 4, associated, by means of a connecting-rod 5, with the crank-shaft 6, shown equipped with 55 the fly or balance wheels 7, the piston-head, connecting-rod, and a portion of the crank-shaft being illustrated in dotted lines in Fig. 1. The upper portion of the cylinder constitutes the explosion or combustion chamber, 60 (indicated at 8,) the same being placed in communication with a laterally-arranged ignition-chamber 9 by means of a passage-way 10. Above the ignition-chamber 9 is the suction-valve casing 11, in which operates the suction-valve 12, while at the opposite or lower side of the ignition-chamber is the exhaust-chamber 13, in which works the exhaust-valve 14.

The exhaust-valve 14 is mounted upon the 70 exhaust-valve stem 15, the same being slidably and rotatably mounted in a bearing 16 at the lower end of the exhaust-chamber and in a bearing-sleeve 17, connected with an arm 18 of a bracket 19, connected to the cylinder 75 or cylinder-frame. The stem 15 is also provided at its upper end within the ignition-chamber with a spark or igniter 20, consisting of a metallic arm which under the oscillatory movement of the stem 15 is adapted 80 to be moved into and out of contact with the other member of the igniting device, which consists of the inner terminal of a binding-post 21, with which an electrical conductor 22 connects. The spark or igniter is of the 85 ordinary make-and-break type and serves to ignite the gas contained within the ignition-chamber, passage-way 10, and explosion or combustion chamber 8 of the cylinder. The exhaust-valve 14 is normally held seated and 90 is restored to its seat by means of a coil-spring 23, which encircles the stem 15 below the exhaust-valve casing. One end of said spring surrounds a hollow boss on the casing 13, which constitutes the bearing 16, above 95 referred to, while the opposite end of the spring is seated against a collar 24, adjustable longitudinally on the stem 15 by means of a set-screw 25, thereby enabling the tension of the spring to be adjusted. The spring 100 23 not only acts as an expansive spring for normally closing the exhaust-valve, but it operates with a torsional action, so that when the cam-like projection 40 has struck and

passed the spring-arm 39 it will turn the igniter member 20 out of contact with the binding-post 38, thereby making and breaking the electrical contact.

5 The stem 15 is provided at a suitable point with a laterally-projecting pin or stop 26, which operates in a notch 27 in the sleeve 17, above described, said notch being of sufficient width or size to admit of the necessary amount 10 of oscillatory or axial turning movement of the stem 15 to throw the igniter members into and out of contact.

At its lower end the stem 15 is provided with a broad foot 28, having a sleeve or hub 15 portion 29, which is threaded to screw upon the lower end of the stem 15, the foot being locked against turning and working loose by means of a jam-nut 30.

In order to impart the requisite reciprocatory movement to the stem 15, the crank-shaft 6 is provided with a spur-pinion 31, which meshes with a spur gear-wheel 32, having twice as many teeth as the pinion 31, so that two revolutions of the crank-shaft are 25 required to impart one revolution to the wheel 32. The last-named wheel is mounted fast on one end of a hub-sleeve 33, which also has rigidly connected therewith a collar 34, capable of being adjusted to the proper position and 30 relation to the other parts by means of a binding-screw 35. The sleeve 33, together with the wheel 32 and collar 34, is journaled on a stud-shaft 36, carried by the bracket 19, and the wheel 32 is provided with a wrist-pin 37, 35 encircled by an antifriction-roller 38, which is adapted once in each revolution of the wheel 32 to come in contact with the foot 28, lifting the latter and imparting an upward movement to the stem 15, which is subsequently retracted or moved downward by 40 means of the spring 23, above described, the downward movement of the stem being limited by the exhaust-valve 14 and its seat. It will thus be seen that the exhaust-valve is 45 unseated but once in every two revolutions of the crank-shaft, the engine thus being of what is known as the "four-cycle" type.

The mechanism for imparting the necessary oscillatory movement to the stem 15 comprises 50 a spring-arm 39, which is carried by the lower end of the stem 15, being preferably connected with the foot 28. Said arm is operated upon once in each revolution of the wheel 32 by means of a cam-like projection 40 on the 55 collar 34, said projection striking against the arm 39 and moving the latter far enough to throw the igniter member 20 into contact with the binding-post 21, thus making and breaking the electrical circuit in which the igniter members are included and exploding the 60 charge of gas or vapor contained within the cylinder. The spring 23, as previously stated, acts to restore the igniter members to their normal positions.

65 The speed-regulating device proper comprises, essentially, a pair of pivotally-mounted segments 41, each approximately of semicir-

cular shape, the said segments being pivotally connected at their adjacent ends to a bracket or lug 42, extending radially outward from 70 the hub of one of the balance-wheels 7. At their opposite or free ends the segments 41 are connected by means of a yoke-spring 43, so as to resist the movement of said segments 75 apart. At their pivotal ends one of the segments is provided with a projecting shoulder 44, which engages with and is engaged by a lip 45 on the other segment, so that as one segment is thrown outward centrifugally a like and corresponding movement is imparted 80 to the other segment. Both segments thus move equally outward or inward and act with equal effect upon the curved extension 46 of a rocker-arm 47, which is fulcrumed intermediate its ends upon the stud-shaft 36, hereinabove described, the rocker-arm being for that purpose provided with a bearing 48, which encircles said stud-shaft, the bearing being indicated in dotted lines in Fig. 2. The opposite or upper end of the rocker-arm 90 47 is provided with a catch 49, which is designed to be moved toward and away from the stem 15, so as to engage beneath a governor-catch 50, carried by the stem 15 and preferably in the form of a collar or flange 95 encircling the stem and located, preferably, beneath the bearing-sleeve 17, as clearly illustrated in both figures. The governor-catch 50 is also preferably made adjustable on the stem 15 by means of a binding-screw 51. The 100 balance-wheel 7 also carries a governor-arm 52, which is pivotally connected at one end at 53 with the wheel and provided at its opposite end with a suitable weight 54. The arm 52 is connected, by means of a pivotal link 55, 105 with one of the segments 41, so that the outward movement of the weighted governor-arm 52 under the influence of centrifugal force will operate upon one of the segments to move the latter outward, the latter in turn 110 acting upon the other segment to move the same in a corresponding direction. In order to regulate the action of the governor-arm 52, the free end thereof is connected to a resistance-spring 56, said spring having its opposite 115 end connected with a tension-bolt 57, which passes through a lug 58, carried by the wheel 7, and is adjustable by means of a thumb-nut 59. The tension device is thus made adjustable, so as to regulate the amount 120 of force which is necessary to hold open the exhaust-valve, the force being in proportion to the speed of the crank-shaft of the engine.

From the foregoing description it will be seen that when the rotation of the crank-shaft 125 becomes too rapid the governor-arm 52, moving outward by centrifugal action, throws the segments 41 outward, causing them to operate against the curved extension 46 of the rocker-arm, with the result that the catch 49 130 on the rocker-arm is moved into the path of the reciprocating governor-catch 50. As this must occur while the exhaust-valve is unseated, when the two catches are in engage-

ment the exhaust-valve is held open and the piston-head is relieved from the frequency of the gas or vapor explosions. As soon as the speed of the crank-shaft decreases sufficiently 5 the segments 41 move inward, and the catch 49 is moved out of engagement with the governor-catch 50, thus allowing the exhaust-valve to seat itself, whereupon the subsequent explosions of gas in the cylinder will drive the 10 piston-head, and the engine will continue or resume its operation. The speed-regulating device is therefore entirely automatic in operation, requiring no attention on the part of the engineer. Moreover, by adjusting the 15 tension device by means of the thumb-nut 59 the speed at which the crank-shaft must rotate in order to throw the exhaust-valve-unseating device into operation may be governed.

20 It will be apparent that the speed-regulator is susceptible of changes in the form, proportion, number, arrangement, and minor details of construction, which may accordingly be resorted to without departing from the principle or sacrificing any of the advantages of 25 the invention.

Having thus described the invention, what is claimed, and desired to be secured by Letters Patent, is—

30 1. In an engine, the combination with the exhaust-valve; of a stem for said valve carrying a member of an electrical igniting device, means for holding the valve normally seated and also for holding the members of 35 the igniter in contact, mechanism for imparting a reciprocatory and an oscillatory movement to the valve-stem, and a governor operated by excessive speed of the crank-shaft of the engine for holding the valve unseated 40 and rendering the igniter inactive.

2. In an engine, the combination with the exhaust-valve and crank-shaft; of pivotally-mounted segments rotatable with the crank-shaft, a centrifugal governor-arm for operating 45 the segments, a rocker-arm actuated by said segments, a catch carried by rocker-arm and another catch on the exhaust-valve stem with which the first-named catch is adapted to engage for holding the exhaust-valve open.

3. In an engine, the combination with the 50 exhaust-valve, exhaust-valve stem and crank-shaft; of a pair of segments embracing the crank-shaft and rotatable therewith, said segments having an interlocked engagement with each other so as to cause them to move simultaneously outward or inward, a centrifugal governor-arm operatively connected with one of the segments, a rocker-arm having a portion thereof arranged in the path of the segments, a catch carried by said governor-arm, 55 and a governor-catch adapted to coöperate therewith and mounted on the exhaust-valve stem.

4. In an engine, the combination with the 60 exhaust-valve, exhaust-valve stem and crank-shaft; of semicircular segments pivotally mounted on and rotatable with the crank-shaft, said segments having an interlocked engagement at one side of the crank-shaft and a yielding connection at the opposite side of 65 the crank-shaft, a centrifugal governor-arm rotatable around the crank-shaft and operatively connected with one of the segments, a rocker-arm actuated by the segments and carrying a catch, and a governor-catch on the 70 exhaust-valve stem adapted to coöperate with the catch on the rocker-arm.

5. In an engine, the combination with the 75 exhaust-valve, exhaust-valve stem and crank-shaft; of a pair of segments embracing the 80 crank-shaft and rotatable therewith, said segments being pivotally mounted and having an interlocked engagement at one end, a yoke-spring yieldingly connecting the opposite ends 85 of the segments, a rocker-arm having a portion thereof arranged in the path of the segments, a catch on said arm, a governor-catch coöperating therewith and carried by the exhaust-valve stem, a governor-arm a resistance-spring associated with the governor-arm, and 90 means for adjusting the tension of said spring.

In testimony whereof I affix my signature in presence of two witnesses.

RICHARD A. F. BEILFUSS.
